(57) **CLAIM**

The ornamental design for a 4-in-1 multi USB charging cable, as shown and described.

DESCRIPTION

FIG. 1 is a front perspective view of a 4-in-1 multi USB charging cable, showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines shown in FIG. 2 are to illustrate portions of the 4-in-1 multi USB charging cable that form no part of the claimed design. The article is shown with a symbolic break in its length, and the appearance of any portion of the article between the break lines forms no part of the claimed design.
